GALVANOMETER

Franz G. Back, New York, N. Y., assignor of one-fourth to Gastro-Photor Laboratories, New York, N. Y.

Application August 30, 1940, Serial No. 354,796

16 Claims. (Cl. 179—100.3)

My present invention relates to galvanometers or like instruments adapted to indicate or record electrical oscillations by modulating a light beam. More particularly, my invention relates to galvanometers used for producing photographic sound records on a sound record carrier, e. g., a film moving with uniform speed by oscillating in the path of a light beam a light-modulating member in accordance with the sound oscillations to be recorded.

It is the main object of my invention to provide for apparatus of the above type a new oscillating member which has no sharp resonance frequency; the resonance curve of this member should be flat in comparison with the curve of other light-modulating members used until now.

It is a further object of my invention to provide a light-modulating oscillating member of a shape which makes it unnecessary to keep it under constant tension and stress, thus avoiding—by using a member without strain—external influences of temperature changes, of mechanical vibrations, or the like, on the frequency characteristic of this oscillating member.

It is another object of my invention to provide a light-modulating oscillating member of such a shape that it should be easily possible to change the frequency characteristic of this member by changing its size and the relative dimensions of the parts of which it is composed.

It is still a further object of my present invention to use such a modulating member which enables mechanical damping without substantial braking of the oscillations.

In order to attain the above objects, I propose to combine in an apparatus of the class described a light source being adapted to emit a light beam, a substantially U-shaped oscillating member being made of a thin metallic strip, said member being arranged in the path of and substantially in one plane with said light beam, a stationary support to which both ends of said U-shaped member are fastened, and means being adapted to oscillate said oscillating member in direction of the width of the strip of which it is made.

A preferred embodiment of my light-modulating means consists in a substantially U-shaped oscillating member bent of a thin metallic strip and consisting of a front strip, two side strips and two fastening strips, forming an angle with said side strips; this oscillating member is arranged in such a manner that said front strip is in the path of said light beam and its face is substantially normal to it.

Furthermore I have found it to be of advantage to provide for this U-shaped oscillating member a stationary support to which the free ends of the fastening strips are fixed in such a manner as to leave the portions of the fastening strips, which are adjacent to the edges formed by the fastening and side strips, unfixed to said stationary support, thereby enabling oscillation of these strip portions.

10 Further characteristic features of my new light-modulating system and the sound recording unit equipped with this system, and advantages of the improvements proposed by me, will appear from the following description and 15 the accompanying drawing, illustrating one embodiment of my invention.

In the drawing:

Fig. 1 shows a cross section of my new galvanometer along line 1—1 of Fig. 7;

Fig. 2 shows a cross section of my new galvanometer along line 2—2 of Fig. 7;

Fig. 3 shows a perspective view of the U-shaped oscillating member;

Fig. 4 shows a plane view of the galvanometer along line 4—4 of Fig. 1;

Fig. 5 shows a cross section of the galvanometer along line 5—5 of Fig. 1;

Fig. 6 shows a plane view of the galvanometer along line 6—6;

30 Fig. 7 shows a plane view of the whole galvanometer;

Figs. 8 to 10 show different arrangements of the oscillating member and the slit in the upper pole shoe.

35 As shown in Figs. 1 and 2, the galvanometer consists of an insulating disk 1 to which the U-shaped oscillating member 2 is fastened by the small inner and outer plates 3; these plates 3 are connected by screws 3'. The outer plates serve simultaneously for electrically connecting the conducting wires 4 with the oscillating member 2.

40 In order to prevent contact between the magnetic system of the galvanometer and the small plates 3, a further insulating disk 5 is arranged around these plates. This disk 5 is provided with an opening 6 for the plates 3 and the oscillating member 2.

45 The magnetic field necessary for producing oscillations of the U-shaped member 2 is produced by the permanent magnets 7 being in intimate contact with the lower pole shoe 8 and the upper pole shoe 9. As shown in Fig. 5 the lower pole shoe 8 is provided with a tongue-

like extension 10 projecting within the U-shaped member 2.

The magnetic system, consisting of the permanent magnet 7 and the pole shoes 8 and 9, produces in the space, in which the oscillating member 2 is arranged, a magnetic field; this magnetic field has its lines of force substantially parallel to the plane of the oscillating member; thereby it causes oscillation of this member in accordance with the current oscillations in the electric circuit to which it is connected by conducting wires 4.

The upper pole shoe 9 is covered by a cover plate 12; they are both provided with concentric longitudinal holes 13 and 14, respectively. In these longitudinal holes the optical system producing the sharp light beam needed for recording purposes can be arranged. Both holes have a square-shaped cross section, and hole 14 ends at its lower end in a slit 15; this slit is parallel to the longitudinal direction of member 2.

In order to have the possibility to produce the square-shaped longitudinal hole 14 and slit 15 in pole shoe 9, this pole shoe is made of two pieces and held together by an angular fastening ring 23. Screws 24 serve for fixing all parts of the galvanometer unit to each other.

The light-modulating member consists, as shown in Fig. 3, of a front strip 16, two side strips 17, forming an angle of 90° with the front strip, and two fastening strips 18 forming also an angle of 90° with said side strips. The fastening plates 3 are provided in such a manner as to leave between these plates and the edges 19 free portions 20, being adapted to oscillate together with the other parts 16 and 17 of member 2. I have found it very important to fasten member 2 to its support in the way described above, because if I fix the side strips 17 of the oscillating member directly to the stationary support, I cannot attain oscillations of the kind needed for my purpose.

According to my observations it is of advantage to make the front strip 16 substantially as long as each of the side strips 17, and to make furthermore the width of the strip of which this member is bent, about one half to one fifth of the length of each of these parts. For an embodiment of my new oscillating member I have used a strip having a width of about $\frac{1}{16}$ ", and made each of the side strips and the front strip about $\frac{1}{4}$ " long; with this oscillating member I attained excellent results. The thickness of the strip is about 0.001".

I want to stress that I do not intend to be limited to oscillating members having the above described shape only: my present invention includes all possible types of U-shaped members, i. e., arc-shaped members or members being composed of arc-shaped and plane strip portions.

As shown in Fig. 8, for sound recording purposes the front strip 16 can be provided with two or more cut-outs 21, producing thereby sound records of the multiple variable area type on the film.

Fig. 9 shows an arrangement with an oscillating member provided with one cut-out, for producing one sound record of the variable area type only. In the arrangement shown in Fig. 10 slit 15 and oscillating member 2 form an acute angle; the sound record produced by oscillating the member 2 thus arranged is also of the variable area type, but its width varies along one edge of the record only.

For damping the oscillations of member 2 I found it of advantage to provide damping material being in contact with one of the stationary parts of the system and with the outer faces of the side strips 17 of the oscillating member; for this purpose I may use a small amount of cotton wool or the like being provided between the pole shoe 8 and oscillating member 2. I may also use rubber drops 22 adhering to the stationary pole shoe 8, or plate 3, as well as to the outer faces of the side strips 17. By using these means, unwanted oscillations of member 2 may be damped, without substantially braking its oscillating movement.

For purposes of sound recording a continuously moving film strip, not shown in the drawing, is arranged under opening 25 in insulating disk 4. The conducting wires 4 are connected to the electric circuit modulated in accordance with the sound to be recorded. Due to the combined action of the magnetic field in which it is arranged and the modulated current flowing through it, the light-modulating member oscillates in accordance with the sound oscillations to be recorded in the direction indicated by arrow 26 in Fig. 3, i. e. in direction of the width of the strip of which it is made. As the optical system within openings 13 and 14 is arranged in such a manner that the light beam passing through the slit in the upper pole shoe is modulated when member 2 oscillates, it may easily be understood that by oscillating this member in accordance with the sound oscillations to be recorded, the shape of the light beam reaching the film will be modulated in the same way, i. e. it will also be modulated in accordance with the sound oscillations to be recorded.

It will be understood that each of the elements of my new light-modulating system, or two or more together, may also find a useful application in other type of apparatus differing from the type described above. It will furthermore be understood that I do not intend to be limited to the exact shape of the oscillating member proposed by me, since various modifications and changes in shape, size and relative dimensions may be made without departing in any way from the spirit of my invention.

Without further analysis the foregoing will so fully reveal the gist of my invention that others can by applying current knowledge readily adapt it for various applications without omitting features, that, from the standpoint of the prior art fairly constitute essential characteristics of the generic or specific aspects of my invention, and therefore such adaptations should and are intended to be comprehended within the meaning and range of equivalency of the following claims.

What I claim as new and desire to secure by Letters Patent is:

1. In an apparatus of the class described a light source adapted to emit a light beam, a substantially U-shaped oscillating member bent of a thin metallic strip and consisting of a front strip, two side strips, and two fastening strips forming an angle with said side strips, said oscillating member arranged in such a manner that said front strip is in the path of said light beam and its face is substantially normal to said light beam, a stationary support to which the free ends of said fastening strips are rigidly fixed in such a manner as to leave the portions of said fastening strips which are adjacent to said edges between fastening and side strips, unfixed to said stationary support, and means adapted to oscil-

late said oscillating member in direction of the width of the strip of which it is bent.

2. In an apparatus of the class described a light source adapted to emit a light beam, a substantially U-shaped oscillating member bent of a thin metallic strip and consisting of a front strip, two side strips, and two fastening strips, said fastening strips arranged at an angle with said side strips and forming thereby an edge between said fastening and said strips, said oscillating member arranged in such a manner that said front strip is in the path of said light beam and its face is substantially normal to said light beam, a stationary support to which the free ends of said fastening strips are rigidly fixed in such a manner as to leave the portions of said fastening strips, which are adjacent to said edges between fastening and side strips, unfixed to said stationary support, enabling thereby oscillation of these free fastening strip portions, and means adapted to oscillate said oscillating member in direction of the width of the strip of which it is bent.

3. In an apparatus of the class described, a light source adapted to emit a light beam, a substantially U-shaped oscillating member bent of a thin metallic strip and including a front strip, two side strips being substantially normal to said front strip, and two fastening strips at the ends of said side strips being substantially normal to said side strips, said oscillating member arranged in such a manner that said front strip is in the path of said light beam and its face is substantially normal to said light beam, a stationary support to which the free ends of said fastening strips are rigidly fixed in such a manner as to leave the portions of said fastening strips, which are adjacent to said edges between fastening and side strips, unfixed to said stationary support, enabling thereby oscillation of these free fastening strip portions, and means adapted to oscillate said oscillating member in direction of the width of the strip of which it is bent.

4. In an apparatus of the class described, a light source adapted to emit a light beam, a substantially U-shaped oscillating member bent of a thin metallic strip, and including a plane front strip, two plane side strips and two plane fastening strips forming an angle with said side strips and being substantially parallel to said front strip, said oscillating member arranged in such a manner that said plane front strip is in the path of and its face substantially normal to said light beam, a stationary support to which the free ends of said plane fastening strips are rigidly fastened in such a manner as to leave the portions of said fastening strips which are adjacent to said edges between fastening and side strips, unfixed to said stationary support, and means adapted to oscillate said oscillating member in direction of the width of the strip of which it is bent.

5. In an apparatus of the class described, a light source adapted to emit a light beam, a substantially U-shaped oscillating member bent of a thin metallic strip and including a front strip, two side strips, and two fastening strips forming an angle with said side strips, the length of said front strip and of each of the side strips being substantially equal, said oscillating member arranged in such a manner that said front strip is in the path of and its face substantially normal to said light beam, a stationary support to which the free ends of said fastening strips are rigidly fastened in such a manner as to leave the portions of said fastening strips which are adjacent to said edges between fastening and side strips, unfixed to said stationary support, enabling thereby oscillation of these free fastening strip portions, and means adapted to oscillate said oscillating member in direction of the width of the strip of which it is bent.

adjacent to said edges between fastening and side strips, unfixed to said stationary support, and means adapted to oscillate said oscillating member in direction of the width of the strip of which it is bent.

6. In an apparatus of the class described, a light source adapted to emit a light beam, a substantially U-shaped oscillating member bent of a thin metallic strip and including a plane front strip, two plane side strips being substantially normal to said front strip, and their length being substantially equal to the length of said front strip, and two plane fastening strips forming an angle with said side strips, said oscillating member arranged in such a manner that said front strip is in the path of and its face substantially normal to said light beam, a stationary support to which the free ends of said plane fastening strips are rigidly fastened in such a manner as to leave the portions of said fastening strips which are adjacent to said edges between fastening and side strips, unfixed to said stationary support, and means adapted to oscillate said oscillating member in direction of the width of the strip of which it is bent.

7. In an apparatus of the class described, a light source adapted to emit a light beam, a substantially U-shaped oscillating member bent of a thin metallic strip and including a plane front strip, two plane side strips, and two plane fastening strips at the ends of said side strips, said side strips being substantially normal to said front strip, and their length being substantially equal to the length of said front strip and the width of said front and side strips being from one half to one fifth of their length, said oscillating member arranged in such a manner that said front strip is in the path of and its face substantially normal to said light beam, a stationary support to which the free ends of said fastening strips are firmly fastened in such a manner as to leave the portions of said fastening strips which are adjacent to said edges between fastening and side strips, unfixed to said stationary support, and means adapted to oscillate said oscillating member in direction of the width of the strip of which it is bent.

8. In an apparatus of the class described, a light source adapted to emit a light beam, a substantially U-shaped oscillating member bent of a thin metallic strip and consisting of a plane front strip, two plane side strips, and two fastening strips, said side strips arranged at the ends of said front strip forming an angle of about 90° with said front strip, the length of said front strip being substantially equal to the length of each of said side strips and the width of said front and side strips being from one half to one fifth of their length, said fastening strips arranged at the ends of said side strips at an angle of about 90° with said side strips, forming thereby an edge between said side strips and said fastening strips, said oscillating member being arranged in such a manner that said plane front strip is in the path of said light beam and its face is substantially normal to said light beam, a stationary support to which both said fastening strips are firmly fixed in such a manner as to leave the portions of said fastening strips, which are adjacent to said edges between fastening and side strips, unfixed to said stationary support, enabling thereby oscillation of these free fastening strip portions, and means adapted to oscillate said oscillating member in direction of the width of the strip of which it is bent.

9. In an apparatus of the class described, a light source adapted to emit a light beam, a substantially U-shaped oscillating member bent of a thin metallic strip and including a front strip, two side strips, and two fastening strips at the ends of said side strips, said oscillating member arranged in such a manner that said front strip is substantially in the path of and its face is substantially normal to said light beam, a stationary support to which the free ends of said fastening strips are firmly fastened in such a manner as to leave the portions of said fastening strips which are adjacent to said edges between fastening and side strips, unfixed to said stationary support, mechanical damping means arranged in contact with at least one of the faces of the side strips of said oscillating member, and means adapted to oscillate said oscillating member in direction of the width of the strip of which it is bent.

10. In an apparatus of the class described, a light source adapted to emit a light beam, a substantially U-shaped oscillating member bent of a thin metallic strip and including a front strip, two side strips, and two fastening strips at the ends of said side strips, said oscillating member arranged in such a manner that said front strip is substantially in the path of and its face is substantially normal to said light beam, a stationary support to which the free ends of said fastening strips are firmly fastened in such a manner as to leave the portions of said fastening strips which are adjacent to said edges between fastening and side strips, unfixed to said stationary support, damping material arranged in contact with said stationary support and with at least one of the faces of the side strips of said oscillating member, and means adapted to oscillate said oscillating member in direction of the width of the strip of which it is bent.

11. In an apparatus of the class described, a light source adapted to emit a light beam, a substantially U-shaped oscillating member bent of a thin metallic strip and including a front strip, two side strips, and two fastening strips at the ends of said side strips being substantially parallel to said front strip, said oscillating member arranged in such a manner that said front strip is substantially in the path of and its face is substantially normal to said light beam, a stationary support to which the free ends of said fastening strips are firmly fastened in such a manner as to leave the portions of said fastening strips which are adjacent to said edges between fastening and side strips, unfixed to said stationary support, at least one damping rubber drop adhering to said stationary support and to at least one of the faces of the fastening strips of said oscillating member, and means adapted to oscillate said oscillating member in direction of the width of the strip of which it is bent.

12. In a galvanometer of the class described, a light source to emit a light beam, a substantially U-shaped oscillating member bent of a thin metallic strip, and including a front strip, two side strips, and two fastening strips at the ends of said side strips being substantially parallel to said front strip, said member being arranged in the path of and substantially in one plane with said light beam, a stationary support to which both ends of said fastening strips are firmly fastened in such a manner as to leave the portions of said fastening strips which are adjacent to said edges between fastening and side strips, unfixed to said stationary support, means for connecting said fastening strips with an elec-

tric circuit the oscillations of which are to be indicated or recorded, and means forming in the space in which said oscillating member is arranged a magnetic field, said magnetic field having its lines of force substantially parallel to the plane of the oscillating member, causing thus oscillation of this member corresponding to the current oscillations in the electric circuit connected to the end portions of said fastening strips.

13. In a galvanometer of the class described, a light source adapted to emit a light beam, a substantially U-shaped oscillating member bent of a thin metallic strip, and including a front strip, two side strips, and two fastening strips at the ends of said side strips being substantially parallel to said front strip, said member arranged in the path of and substantially in one plane with said light beam, a stationary support to which both ends of said fastening strips are firmly fastened in such a manner as to leave the portions of said fastening strips which are adjacent to said edges between fastening and side strips, unfixed to said stationary support, means for connecting said fastening strips with an electric circuit the oscillations of which are to be indicated or recorded, and a permanent magnet arranged in such a way as to form in the space, where the oscillating member is arranged, a magnetic field having its lines of force substantially parallel to the plane of the oscillating member, causing thus oscillation of this member corresponding to the current oscillations in the electric circuit connected to the end portions of said fastening strips.

14. In a galvanometer of the class described, a light source adapted to emit a light beam, a substantially U-shaped oscillating member bent of a thin metallic strip, and including a front strip, two side strips, and two fastening strips at the ends of said side strips being substantially parallel to said front strip, said member arranged in the path of and substantially in one plane with said light beam, a stationary support to which both ends of said fastening strips are firmly fastened in such a manner as to leave the portions of said fastening strips which are adjacent to said edges between fastening and side strips, unfixed to said stationary support, means for connecting the ends of said fastening strips with an electric circuit the oscillations of which are to be indicated or recorded, a permanent magnet and at least one pole shoe, said magnet and pole shoes arranged in such a manner as to create in the space where the U-shaped oscillating member is arranged a magnetic field.

15. In a galvanometer system for sound recording by modulating a light beam in accordance with the sound oscillations to be recorded, a light source adapted to emit a light beam, a carrier for the sound records to be produced, said carrier arranged in the path of said light beam and adapted to be moved with uniform speed, a substantially U-shaped oscillating member bent of a thin metallic strip and including a front strip, two side strips, and two fastening strips at the ends of said side strips being substantially parallel to said front strip, said front strip being provided at one of its edges with cut-outs corresponding to the shape and type of the variable area sound records to be produced, said U-shaped oscillating member arranged between said light source and said carrier in such a manner that said front strip with the cut-outs is in the path of and its face substantially normal to said light beam, a stationary support to which

the free ends of said fastening strips are firmly fastened in such a manner as to leave the portions of said fastening strips which are adjacent to said edges between fastening and side strips, unfixed to said stationary support, and means adapted to oscillate said oscillating member in direction of the width of the strip of which it is bent.

16. In a galvanometer system for sound recording by modulating a light beam in accordance with the sound oscillations to be recorded, a light source adapted to emit a light beam, a carrier for the sound records to be produced, said carrier arranged in the path of said light beam and adapted to be moved with uniform speed, a substantially U-shaped oscillating member bent of a thin metallic strip and including a front strip, two side strips, and two fastening strips at the ends of said side strips being substantially parallel to said front strip, 20 said U-shaped member arranged in such a man-

ner that said front strip is in the path of and its face is substantially normal to said light beam, a member forming a slit substantially parallel to said front strip and arranged in the path of said light beam between the light source and said U-shaped member, a stationary support to which both ends of said fastening strips are firmly fastened in such a manner as to leave the portions of said fastening strips which are adjacent to said edges between fastening and side strips, unfixed to said stationary support, means for connecting the ends of said fastening strips with an electric circuit the oscillations of which are to be indicated or recorded, a permanent magnet and two pole shoes, said magnet and said pole shoes arranged in such a manner as to create in the space where the oscillating member is arranged a magnetic field having its lines of force substantially parallel to the plane of this member.

FRANZ G. BACK.
